UNITED STATES PATENT OFFICE

106,250

DESIGN FOR A KNOB FOR RADIO SETS OR THE LIKE

Harry Davies, Chicago, Ill.

Application May 29, 1937, Serial No. 69,624

Term of patent 3½ years

To all whom it may concern:

Be it known that I, Harry Davies, a citizen of the United States, residing at Chicago, in the county of Cook and State of Illinois, have invented a new, original, and ornamental Design for a Knob for Radio Sets or the like, of which the following is a specification, reference being had to the accompanying drawing, forming a part thereof, in which

Figure 1 is a plan view of a knob made in accordance with my design;

Fig. 2 is a side elevational view thereof; and Fig. 3 is a perspective view of a knob embodying my design, the predominating feature being shown in full lines.

I claim:

The ornamental design for a knob for radio sets or the like substantially as shown and described.

HARRY DAVIES.
